CLAIM

We claim the ornamental design for a portable compact testing device, as shown and described.

DESCRIPTION

FIG. 1 is a front, right, isometric view of a portable compact testing device in a capped configuration in accordance with the present design.

FIG. 2 is a right side elevation view of the portable compact testing device of FIG. 1. The left side elevation view is a mirror image thereof.

FIG. 3 is a top plan view of the portable compact testing device of FIG. 1.

FIG. 4 is a bottom plan view of the portable compact testing device of FIG. 1.

FIG. 5 is an enlarged front elevation view of the portable compact testing device of FIG. 1.

FIG. 6 is an enlarged rear elevation view of the portable compact testing device of FIG. 1.

FIG. 7 is a front, right isometric view of the portable compact testing device of FIG. 1 in an alternate, open configuration.

FIG. 8 is an isometric view of the portable compact testing device of FIG. 1 in an alternate, open, uncapped configuration in accordance with the present design.

FIG. 9 is a top plan view of the portable compact testing device of FIG. 8.

FIG. 10 is a bottom plan view of the portable compact testing device of FIG. 8.

FIG. 11 is a right side elevation view of the portable compact testing device of FIG. 8. The left side elevation view is a mirror image thereof.

FIG. 12 is an enlarged rear elevation view of the portable compact testing device of FIG. 8.

FIG. 13 is an enlarged front elevation view of the portable compact testing device of FIG. 8; and,

FIG. 14 is a front, right, isometric view of the portable compact testing device of FIG. 8 in an alternate, closed configuration.

(Continued)

The broken lines in the drawings depict portions of the portable compact testing device that form no part of the claimed design.
